(57) **CLAIM**

We claim the ornamental design for a hand operated electrical control, as shown and described.

DESCRIPTION

FIG. 1 is a perspective view showing front, top and right end portions of our new design;

FIG. 2 is a front side elevational view thereof;

FIG. 3 is a top plan view thereof;

FIG. 4 is a right end elevational view thereof;

FIG. 5 is a left end elevational view thereof; and,

FIG. 6 is a bottom view thereof.

The broken line showing of the environment is for illustrative purposes only and forms no part of the claimed design.
